J. T. OHMAN.
ATTACHMENT FOR THIMBLES.
APPLICATION FILED JULY 23, 1910.

998,709.

Patented May 30, 1911.

UNITED STATES PATENT OFFICE.

JOHN T. OHMAN, OF WORCESTER, MASSACHUSETTS.

ATTACHMENT FOR THIMBLES.

993,709.

Specification of Letters Patent. Patented May 30, 1911.

Application filed July 23, 1910. Serial No. 573,522.

To all whom it may concern:

Be it known that I, JOHN T. OHMAN, a citizen of the United States, residing at Worcester, in the county of Worcester and 5 State of Massachusetts, have invented a new and useful Attachment for Thimbles, of which the following is a specification.

This invention relates to an attachment for thimbles for cutting thread and pulling 10 needles.

The principal objects of the invention are to provide a simplified form of device for this purpose which can be made out of a single blank of sheet metal, and this will 15 consist of a single part only; and to provide a more convenient and simple construction of needle puller than has been done heretofore.

The invention also involves improvements 20 in details of construction as will appear hereinafter.

Reference is to be had to the accompanying drawings in which—

Figure 1 is a side view of a thimble with 25 one form of the invention applied thereto. Fig. 2 is an edge view of the attachment and thimble. Fig. 3 is a view of the side opposite to that shown in Fig. 1. Fig. 4 is a plan of a blank from which the attachment can 30 be made, and Fig. 5 is a side view of a thimble showing a modification of the attachment.

In the form of the invention shown in the first four figures, the thimble A is provided 35 with a removable ring or clip 10 having integral hooks 11 at the edges adapted to be bent over the edge of the thimble so as to secure the attachment thereto. With this ring is integrally connected a base 12 which is 40 turned up at right angles to form a side-piece. The side piece has an inclined slot 14 having a slanting cutting edge 15. The side 13 also has a turned down end 16 spaced from the side 13 to form a guide for a sliding 45 part 17 which is integral with an extension 18 projecting from the opposite side of the ring. The forward inclined edge 19 of the part 17 is a cutting edge and is adapted to come into cutting coöperation with the edge 50 15 when the blade 17 is pushed forward. This can be accomplished by pressing down on a bow-shaped projection 20 on the extension 18. The base 12 also is provided with a turned over end 21 which has a perforation 55 22 just at the bend. This perforation is for

the purpose of admitting a needle as shown in dotted lines in Fig. 1. It has been found in practice that the admission of a needle from the side is somewhat inconvenient and consequently this arrangement has been provided to permit the needle to be inserted from the end. After being inserted, the end 21 is pressed down to hold the needle for the purpose of gripping it so that it can be pulled as will be understood. A needle 60 attachment constructed in this way can be made of a single blank B of sheet metal of the form shown in Fig. 4 in which the parts 10^a—11^a—12^a—13^a—15^a—16^a—17^a—18^a—19^a— and 21^a are bent up in one way or 65 another to form the parts having the corresponding numbers in Figs. 1, 2 and 3. Thus it will be seen that these parts are all integral.

In the form shown in Fig. 5, the needle 75 puller is shown as applied to an attachment C of a different character which has an inward bend 24 for gripping the needle. A perforation is provided in the center of the back bend 23 as in the other case and acts 80 in the same way.

In both forms the hooks 11 are used to hold the attachment on while pulling the needle. At this time the action of the operator in pressing on the spring to grip the 85 needle has the effect of holding the hooks firmly on the thimble so that the attachment will not be pulled off.

While I have illustrated and described two forms of the invention, I am aware that 90 many other modifications can be made therein by any person skilled in the art without departing from the scope of the invention as expressed in the claims. Therefore, I do not wish to be limited to all the details 95 of construction shown and described, but

What I do claim is:—

1. As an article of manufacture, an attachment for thimbles, comprising a reversely bent member located near the top 100 of the thimble and having means whereby a needle can be admitted longitudinally to be gripped by the bent member, a fixed knife blade, and a longitudinally movable knife blade adapted to coöperate therewith. 105

2. As an article of manufacture, an attachment for thimbles comprising a base adapted to be supported along the side of the thimble and having means at the end near the top of the thimble for gripping a 110

- needle, a blade projecting therefrom, and a movable blade adapted to coöperate therewith.
3. As an article of manufacture, an attachment for thimbles, comprising a base adapted to be located along the side of a thimble, a piece projecting at right-angles therefrom and having a cutting edge, and a second piece resiliently connected therewith and having a movable cutting edge adapted to coöperate with the first named cutting edge.
4. As an article of manufacture, an attachment for thimbles, comprising a body adapted to lie along the surface of a thimble having an integral member projecting substantially at right-angles therefrom and having a slot therein at an inclination, one edge of said slot being a cutting edge, a resilient projection extending from the other end of said body, and a blade integrally mounted on said extension and adapted to move along the surface of said member and to coöperate with the said cutting edge.
- 25 5. As an article of manufacture, an attachment for thimbles, comprising a body adapted to lie along the surface of a thimble having an integral member projecting at right-angles therefrom and having a slot therein at an inclination, one edge of said slot being a cutting edge, a resilient extension, and a blade integrally mounted on said extension and adapted to move along the surface of said member and to coöperate with the said cutting edge.
- 30
- with the said cutting edge, said member having an overlapping projection constituting a guide for said blade.
6. As an article of manufacture, an attachment for thimbles comprising a base adapted to be supported along the side of the thimble, and having integral means at the end near the top of the thimble for gripping a needle, an integral blade projecting therefrom, an integral movable blade adapted to coöperate therewith, and a ring connected with said piece and adapted to extend part way around the thimble and provided with hooks thereon for securing it to the thimble.
7. As an article of manufacture, an attachment for thimbles comprising a base adapted to be supported along the side of the thimble, and having means at the end near the top of the thimble for gripping a needle, a blade projecting therefrom, a movable blade adapted to coöperate therewith, and a ring integral with said piece and adapted to extend part way around the thimble and provided with hooks thereon for securing it to the thimble.
- 50
- 55
- 60
- In testimony whereof I have hereunto set my hand, in the presence of two subscribing witnesses.

JOHN T. OHMAN.
